UNITED STATES PATENT OFFICE.

JULIAN ALEXANDER, OF PHILADELPHIA, PENNSYLVANIA.

BELT-REEL.

1,070,762.

Specification of Letters Patent. Patented Aug. 19, 1913.

Application filed February 4, 1913. Serial No. 746,225.

To all whom it may concern:

Be it known that I, JULIAN ALEXANDER, a citizen of the United States, residing in Philadelphia, Pennsylvania, have invented 5 certain Improvements in Belt-Reels, of which the following is a specification.

My invention relates to the winding or rolling of belts or the like.

The chief object of my invention is to 10 provide a reel for quickly and easily winding long belts or other film or strip material into roll form and which may be readily transported or stored.

Another object, is that mechanism constructed in accordance with my invention 15 will be durable and adjustable to suit belts of different sizes.

These objects, and other advantages which 20 will be described in the following specification, I attain in the following manner, reference being had to the accompanying drawings in which,

Figure 1, is a side elevation of my invention 25 showing the elements in the position occupied when a belt is being wound; Fig. 2, is a view similar to Fig. 1 but showing the elements in another position; Fig. 3, is a sectional elevation taken on the line *a—a* Fig. 1; Fig. 4, is an enlarged fragmentary 30 sectional view taken on the line *b—b* Fig. 3. Fig. 5, is an inverted sectional plan view taken on the line *c—c* Fig. 4; Fig. 6, is an enlarged fragmentary view of a part of my 35 invention; and Fig. 7, is an enlarged section of a wheel bushing which I employ.

Referring to the drawings, 1 and 2 are supporting standards which may be rigidly secured to the floor and are each provided with a lever 3 pivotally connected at 4 to 40 the said supporting standards. The levers 3 are each provided with a handle 3^a and a yoke portion 5 forming a socket or open bearing 3 which acts as a bearing for an axle or shaft 7 and one face of each yoke 45 portion is provided with a lifting lip 5^a. Each lever 3 is provided with an abutment portion 8 and these abutment portions are adapted to respectively engage stops 9 and 10 formed on each of the standards 1 and 2 when the handles are moved into the respective 50 positions as shown in Figs. 1 and 2,

and the said abutment portions 8 and stops 9 and 10 are so positioned that when the levers 3 are in the said respective positions the axes of the shaft 7 and the pivots 4 will 55 be indifferent vertical planes.

Wheels 11 and 12 are mounted on the shaft 7 and each comprise spokes 13, tire 14 and hub 15. The hubs 15 may be secured to the said shaft 7 by means of set 60 screws or keys of any well known form which will allow the said hubs to be moved longitudinally along the shaft 7 and clamped in any position desired. In cases when a heavy belt is to be wound or any 65 other time when it is desired to strengthen the reel, I insert a sleeve or bushing 22 so that the latter will tend to bind and secure the hubs of the wheels together. The said bushing may be allowed to rotate on the 70 shaft or can be secured thereto and the entire shaft be allowed to rotate within the sockets 6. Spacing bolts 16 pass through and are secured to respective spokes of each wheel. A winding core 17 is preferably 75 made from a strip of metallic material and is shaped into a substantially circular form in such a manner that its free ends overlap and are slightly spaced apart as clearly shown in Figs. 1, 3 and 4. The core 17 is 80 held in the position just described by means of the spokes 13 which are pressed against the edges 18 and 19 by the action of the bolts 16.

A pulley 20 is secured to the wheel 12 by 85 means of staple bolts 21, which bind the spokes 13 and the said pulley 20. I have shown a grooved pulley in the present instance, but it will be understood that a pulley or driving means of any type may be 90 employed and that it may be attached to either or both of the wheels if desired.

The diameters of the wheels 11 and 12 are equal and are such that, when the levers 3 are thrown into the position as shown in 95 Fig. 2, the wheels will rest bodily on the floor and may be rolled thereon, as it will be noticed that the sockets 6 are in such a position as to allow the shaft to move out and away therefrom when in the position 100 shown in Fig. 2.

The operation of my invention is as fol-

lows: When it is desired to wind or roll a belt, the bolts 16, which are substantially the same length as the width of the belt to be wound, are secured to the wheels as above described after the core 17 of the proper width has been inserted. The shaft 7 is then placed within the sockets 6 and the handles are moved into the position shown in Figs. 1 and 3; thereby lifting the wheels off of the floor and so that they, together with the core 17, are free to rotate. One end of the belt is then inserted within the space between the overlapped ends of the metal core 17 as clearly shown in Figs. 1 and 4, and motion is imparted through the medium of the pulley 20 and wheels 11 and 12 to the core 17, and the belt is wound on the latter due to the fact that the overlapping ends of the core 17 form a clamp for the said end of the belt which is inserted therebetween. After the belt has been wound, the free end may be clamped to the wound portion of the belt by a clamp of any construction and the handles 3^a are moved so as to actuate and move the levers 3 into the position as shown in Fig. 2, and the belt in its wound state may be rolled to any place desired on the wheels 11 and 12. If it is desired to remove the belt from the wheels for storage purposes the same may be done by removing the bolts 16 and separating the wheels 11 and 12. The core 17 may be allowed to remain within the belt or it may be slipped therefrom as desired. The lips 5^a are so arranged that they will prevent the shaft 7 from slipping out of the sockets 6 when the mechanism is being lifted from the position shown in Fig. 2 to that shown in Fig. 1. The wheels 11 and 12, in addition to serving as a means of conveyance, act as fly wheels and thereby tend to produce an even rotation during the winding of a belt.

My invention is particularly serviceable when handling belts of large sizes in which the weight of the wound belt is too heavy to be easily handled by men, and is also useful when making belts and in testing the same, as the proper tension may be attained by means of my mechanism and when the portions of the belt have been either tested or completed the same may be directly wound thus not necessitating rehandling as is now the general practice. Also with my invention belts may be wound in the proper form and they will be compact and even.

I claim:—

1. A belt reel comprising a rotatable core; wheels secured to the core; an axle for the wheels; supporting standards; members movably mounted on the supporting standards and having open bearings formed therein for supporting the axle; and means

for raising and lowering said axle support- 65 ing members.

2. A belt reel comprising a rotatable core; wheels secured to said core; an axle for the wheels; supporting standards; with levers movably mounted on said standards and 70 having open bearings formed therein for supporting said axle, said levers being operable to raise and lower the axle.

3. A belt reel comprising a rotatable core; wheels secured to the rotatable core; an 75 axle for the wheels; supporting standards mounted on the floor; and levers movably mounted on the standards and forming a bearing for the said axle, said levers being movable to bring the wheels into and out of 80 contact with the floor.

4. A belt reel comprising a rotatable core; wheels secured to the core; a pulley secured to the wheels; an axle for the wheels; supporting standards mounted on the floor; 85 levers pivotally secured to the supporting standards and being provided with sockets and lifting lips, said axle being adapted to engage said sockets; and handles on said levers whereby the levers are moved to 90 lower or raise the said axle and to move the wheels into and out of contact with the floor, said lips acting to hold the axle within the sockets during the said raising movement.

5. A belt reel comprising a rotatable core; wheels secured to the core; a pulley secured to the wheels; an axle for the wheels; supporting standards mounted on the floor; levers pivotally secured to the supporting standards and provided with sockets, said 100 axle being adapted to engage said sockets; handles on said levers whereby the levers are moved to lower or raise the said axle and to move the wheels into and out of contact with the floor; stops on said supporting standards; and abutment members on said levers, said abutment members being positioned to contact with the respective stops on the supporting standards to prevent 110 the wheels from contacting with the said floor during the winding of a belt.

6. A belt reel comprising a rotatable core having a space for the insertion of the end of the belt; wheels secured to the said core; an axle for the wheels; supporting standards; levers movably mounted on said standards and forming a support for said axle; and means for moving the said levers to move the said wheels into or out of contact with the floor.

7. A belt reel comprising a rotatable strip core having overlapping ends and a space between the said overlapped ends for the insertion of the end of a belt; wheels; spacing bolts securing the said wheels and the core; an axle for the wheels; supporting standards mounted on the floor; levers

pivottally connected to the supporting stand-
ards and having bearings formed therein
for the reception of said axle; a pulley se-
cured to said wheels; and means for actuati-
ng said levers to move the said axle and
thereby move the wheels into and out of
contact with the floor.

In testimony whereof, I have signed my
name to this specification, in the presence
of two subscribing witnesses.

JULIAN ALEXANDER.
